VITRIFIED TRAFFIC MARKER

Dean R. Sever, New Philadelphia, and Donald J. Renkert, near Canton, Ohio; said Renkert assignor to The Metropolitan Paving Brick Company, Canton, Ohio, a corporation of Ohio

Application July 26, 1941, Serial No. 404,186

8 Claims. (Cl. 94—1.5)

The invention relates to traffic markers for use upon roadways to clearly mark lanes of traffic, and more particularly to a marker which is readily visible at night.

With increasingly heavy traffic it is essential that roadways be provided with means for marking lanes of traffic which will be easily visible at night under the lights of an approaching vehicle as well as by overhead lighting along the roadway where such is used.

It is known that attempts have been made to provide various forms of traffic markers having certain reflecting properties, but such devices as have been placed in use for this purpose have not been satisfactory and usually require a separate part applied to or embedded in the roadway.

The present invention contemplates the provision of a paving brick or block adapted to be built into the roadway and having an integral portion thereof forming a traffic marker clearly visible during the day and being of such shape and composition to provide sufficient reflection and diffusion of light to make the same plainly visible at night.

It has been found that the material best suited for this purpose is fire clay and that the reflection and diffusion properties thereof are improved by de-airing the clay so as to increase the density thereof.

It is, therefore, an object of the invention to provide a traffic marker in the form of a paving brick or block preferably formed of fire clay which is de-aired before it is molded into the brick or block, and provided upon its top surface with a projection shaped so as to reflect light back to an approaching vehicle as well as diffuse light so as to make the projection clearly visible at night.

Another object is the provision of such a marker in which reflecting surfaces of the projection are convexed and substantially vertical.

A still further object is the provision of a marker of this character in which the projection is provided with four similar reflecting surfaces so as to permit the improved paving bricks or blocks to be located either transversely or longitudinally relative to the roadway and provided for reflection of light back to a vehicle approaching along the roadway from either direction.

Still another object is to provide a brick or block of this kind in which the projection has a rounded or convex top to assist in diffusion of light.

Another object of the invention is to provide

such a brick with a recess in its underside of proper size and shape to accommodate the projection upon the top of a similar brick so that the bricks may be easily stacked or piled in the drier, kiln or for storage or shipping.

This is particularly important in the burning of the bricks as it prevents discoloration of the reflecting surfaces of the projection by flashing during the burning in the kiln.

10 The above objects together with others which will be apparent from the drawing and following description, or which may be later referred to, may be attained by constructing the improved traffic marker in the manner illustrated in the accompanying drawing in which

Figure 1 is a top plan view of a traffic marker brick embodying the invention;

Fig. 2, a side elevation partly in section showing two bricks placed one upon another in a position they would assume in a drier, kiln or for storage or shipping;

Fig. 3 is an end elevation partly in section of the bricks shown in Fig. 2; and

25 Fig. 4 is a perspective view of a portion of a roadway showing the improved traffic marker located in the center line of the road.

Similar numerals refer to similar parts throughout the several views.

The improved traffic marker is made in the 30 form of a rectangular paving brick or block indicated generally at 10, and formed of a suitable light colored material of sufficient density to provide the desired reflection and diffusion properties.

35 It has been found by experience that the material best suited for forming these bricks or blocks is a good grade of fire clay, and the same is preferably de-aired before the traffic markers are formed therefrom in order to provide sufficient density to produce necessary diffusion as well as reflection.

40 A projection indicated generally at 11 is formed upon the top of each brick or block being preferably centrally located thereon as shown in the drawing.

45 This projection is of generally square or rectangular form, having the four similar convex side faces 12 which are substantially vertical and preferably of the shape shown in the drawing, being highest at the center as indicated at 13, the upper edge of each of these faces being curved downward toward the corners 14.

50 The top surface 15 of the projection 11 is convex, being curved downwardly toward each corner 14.

Each brick is provided in its lower side with a recess or socket 16 of substantially rectangular shape, being slightly larger than the projection 11 and slightly deeper than the height of said projection and so positioned that when several of the improved blocks or bricks are stacked one upon the other the projection 11 on the top of each brick will be received in the recess 16 in the bottom of the brick above.

It should be understood, of course, that the bricks may be piled upon their side faces and the projections received in the recess of adjacent bricks.

This permits of stacking the bricks in the drier or kiln, or provides for storing or shipping the bricks in such condition that they may be easily stacked and will not require any more room than the conventional brick.

This recess also provides for entirely enclosing the projection of the adjacent brick during the burning of the bricks in a kiln thus preventing discoloration of the projection and flashing during the burning operation.

In use the improved traffic markers may be built into the roadway, being laid end to end or side to side as desired with the projections 11 extending slightly above the surface of the road.

For the purpose of illustration the improved traffic markers are shown in Fig. 3 as forming the center line 17 of a road dividing the same into right and left hand traffic lanes 18 and 19 respectively, but it should be understood that these traffic markers may be used in the same manner to indicate the side edges of a road or to divide a road into any desired number of traffic lanes.

It has been found that at night the headlights of an approaching automobile will illuminate the projections 11 so that the line marked thereby is clearly visible.

Regardless of the position of the traffic markers in the road or the direction from which the vehicle approaches one face 12 of each projection 11 will reflect the light from the vehicle's headlights back to the driver while the rounded top surface 15 of each projection will produce sufficient diffusion of light to make the markers clearly visible.

The substantially vertical faces 12 present no place for dirt or dust to collect and will remain bright and clean in use providing sufficient reflecting surfaces to properly function as above described.

We claim:

1. A traffic marker comprising a block formed of fire clay and arranged to be embedded in a roadway with its top surface flush with the surface of the roadway, an integral four sided fire clay projection centrally located upon the top of the block, the side faces of the projection being substantially vertical and convex and tapering in height from the center toward each end, and a convex top surface upon the projection con-

forming at its edges to the contours of the vertical side faces.

5 2. A traffic marker comprising a block formed of fire clay and arranged to be embedded in a roadway with its top surface flush with the surface of the roadway, an integral fire clay projection formed upon the top of the block, said projection having opposed, substantially vertical, convex faces.

10 3. A traffic marker comprising a block formed of fire clay and arranged to be embedded in a roadway with its top surface flush with the surface of the roadway, an integral fire clay projection formed upon the top of the block, said projection having opposed, substantially vertical, convex faces and a convex top surface upon said projection.

15 4. A traffic marker comprising a block formed of fire clay and arranged to be embedded in a roadway with its top surface flush with the surface of the roadway, an integral fire clay projection formed upon the top of the block, said projection having opposed, substantially vertical, convex faces, said faces tapering in height from the center toward opposite ends.

20 5. A traffic marker comprising a block formed of fire clay and arranged to be embedded in a roadway with its top surface flush with the surface of the roadway, an integral fire clay projection formed upon the top of the block, said projection having opposed, substantially vertical, convex faces, said faces tapering in height from the center toward opposite ends and a convex top surface upon said projection.

25 6. A traffic marker comprising a block formed of fire clay and arranged to be embedded in a roadway with its top surface flush with the surface of the roadway, an integral, four sided fire clay projection formed upon the top of the block, the side faces of the projection being substantially vertical and convex.

30 7. A traffic marker comprising a block formed of fire clay and arranged to be embedded in a roadway with its top surface flush with the surface of the roadway, an integral, four sided fire clay projection formed upon the top of the block, the side faces of the projection being substantially vertical and convex, and a convex top surface upon said projection.

35 8. In combination with a roadway, means for marking lanes of traffic in the roadway, said means comprising a course of fire clay blocks embedded in the roadway in juxtaposition to each other at one edge of a traffic lane, the top surface of each fire clay block being substantially flush with the surface of the roadway, each fire clay block having an integral fire clay projection formed upon its top said projection having opposed substantially vertical convex faces being located transversely of the traffic lanes, and a convex top surface upon said projection.
